ART AND METHOD OF MAKING SHOES

Filed Oct. 5, 1931

UNITED STATES PATENT OFFICE

BENJAMIN W. FREEMAN, OF CINCINNATI, OHIO

ART AND METHOD OF MAKING SHOES

Application filed October 5, 1931. Serial No. 567,050.

This invention relates to methods of forming and fastening the bottoms of shoes, and more particularly to methods of fitting heel seats for pre-formed heels of materials such as wood, aluminum and the like.

Among the objects of this invention is the attachment of the heel and sole in an interlocking and cooperating manner, to the end, that the sole is securely held against separation from the heel.

Another, and important object of the invention is to provide a process which will eliminate the costly hand labor required in the heel seating or rand shaping operation preparatory to the attachment of the heel, which heretofore has usually required hand labor of a highly skilled operator. In a prior Patent, No. 1,788,234, of January 6th, 1931, there is disclosed a method of attaching soles and heels to a shoe with this purpose in view, and the present invention contemplates improvements in the method and resultant articles disclosed therein.

Heels of the style referred to are usually covered with an ornamental veneer conforming to the upper of the shoe, and consequently it is impractical to burnish, trim or otherwise treat the sole to a finishing operation which might injure the veneer of the heel, and in fitting these pre-formed heels to shoes it is customary to cup out the heel, and to shape the heel seat convexly, the purpose being to ensure close contact between the periphery of the concave heel bottom and the upper material which extends into the heel seat. Obviously, it is undesirable to extend the outsole beneath the heel in such a manner as to be visible between the heel and upper, when the shoe is finished and heretofore a short sole which terminates immediate adjacent the heel breast, has generally been used, or a long sole attached to the upper and trimmed away at the heel seat end, thus wasting material. Aside from the waste and the necessity of utilizing skilled labor to shape the rand, or fit the heel seat to the heel, it is difficult, when a short sole is so used, to prevent separation of the sole and heel, and one of the objects of this invention is to provide such an extension of the sole beneath the

heel as to provide an interlock securing the sole in position without however, exposing the sole extension to view.

A further object is to secure the sole and utilize same as a part of the heel fitting in the manner described to effect the saving in material and other advantages of a short outsole, while at the same time providing a practical principle of shoe manufacture in which the disadvantages of a short outsole are overcome.

The method described contemplates adaptation to various styles of heels such as, Cuban or military, Louis, etc., with but slight variation in detail.

To the attainment of the foregoing and other objects which will appear as the description proceeds, references may be made to the accompanying drawing, in which

Fig. 1 is a plan view of a finished heel seat;

Fig. 2 is a section illustrating one step in the method of fitting the heel seat;

Fig. 3 is a similar view showing a subsequent step;

Fig. 4 is a perspective illustrating the step of completing the seat; and

Fig. 5 is a section showing application of the heel to the seat with one style of heel.

The method herein is described particularly with reference to a military or Cuban heel, it being understood of course that the method is applicable to any type of heel.

Briefly stated, the method comprises splitting the sole across the back, making up the shoe in a conventional manner with the sole attached and ready for the heel seat fitting operation, removing the extending portion of the sole beneath the flap produced by splitting so that an abutment will be left on the sole, and against which the breast of the heel may be placed flush, trimming the flap so that the side portions or edges thereof will come flush or within the extent of the heel breast, and then attaching the heel to the shoe with the flap therebeneath.

Referring more specifically to the drawing, wherein like reference numerals designate like parts, 10 represents the outsole of a shoe, and 12 the upper terminating in an inturned portion 14. A wood heel of the Cuban style

is indicated at 16, said heel being concaved as indicated at 18 to fit the heel seat 20.

In carrying out the herein described method the sole 10 is split to form two flaps 22 and 24. The flap 24 is cut away sufficiently to leave a shoulder or abutment 24a and the flap 22 is trimmed about its edges a sufficient extent to permit a fitting thereof within the concavity 18 and with no edge 10 portion thereof exposed when the heel is fitted.

The flap 22 may be trimmed to fit the concaved or shaped portion of the heel seat either before or after the sole is attached, as 15 there is no close fitting to this operation.

The flap 22 is then laid into the heel seat and the heel fitted thereover with the breast 26 engaging the abutment formed by 24a and the bent-over portion of flap or extension 22.

20 It will be observed that when the heel is fitted to the seat that the flap or extension 22 of the sole forms a firm interlock with the heel and shoe at the heel-breast joint. This interlock may be enhanced by the use 25 of a tack or heel nail 28 driven from within the shoe through the tongue or flap 22 into the heel. Such nails may be inserted in other directions than as indicated or any other suitable means of fastening may be used.

30 The extension 22, in fact the original sole prior to the formation of the flaps 22 and 24, need not extend beyond the heel breast joint any further than is necessary to produce the interlocking effect, and does not 35 have to be the full or exact outline as shown in Fig. 1.

A knife of the proper design readily cuts the heel seat end of the sole to the proper shape. This sole cutting operation can be 40 accomplished either after the sole has been marked or by means of adjustable gauges covering the different sizes and widths, and locating the knife with relation to the heel seat end of the sole so as to cut it in the proper place.

The exact order or sequence of operations upon the sole, whereby the sole is split, trimmed and shaped to provide the abutment 24a, attached to the upper of the shoe and 50 properly aligned with the heel may be varied and I do not intend to be limited to any particular order, as obviously certain of the steps may be performed either before or after the sole is attached to the shoe. But as indicated above the preferred method contemplates first splitting the sole to form the flaps, then making up the shoe in the conventional manner with the sole attached and ready for the heel seat fitting operation, removing the 55 extending portion of the sole beneath the flap on the outer side and trimming such outer flap, and then attaching the heel to the shoe with the flap therebeneath and in the relation shown in Fig. 5 to the abutment 24a.

60 65 As stated, the method described is a very

simple way of attaching heels and fitting the seats and as the extension or flap does not have to extend very far under the heel, short soles can be utilized if the manufacturer cares to use them, and the manufacturer can use his own judgment as to how much he wishes to save in sole leather and how far he desires the extension 22 on the sole to extend back under the heel. 70

Having thus described my invention, what I claim as new and desire to secure by Letters Patent of the United States, is:—

1. The method of fitting heel seats of shoes which comprises splitting the sole across the back to form a pair of flaps, applying the sole to a shoe, removing that portion of the flap adjacent the shoe, back of the breast line, trimming the edge of the other flap, and applying a heel to the shoe with the trimmed flap therebeneath and the edge of the first mentioned flap flush with the heel breast. 80

2. The method of fitting heel seats of shoes which comprises operating upon the sole at the heel end thereof to form a shoulder thereacross and an extension of the sole beyond said shoulder and to attach the sole to the shoe with the extended portion outward, and applying a heel to the shoe with said extended portion therebeneath and with the heel breast in abutting relation to the shoulder. 90

3. The method of fitting heel seats of shoes which comprises forming an extension of a short sole, beyond the normal heel end thereof, operating upon the sole to attach same to a shoe and to shape said extension to provide a lesser thickness throughout than the remainder of said sole, and to leave a shoulder thereacross, and applying a heel to the shoe with the heel breast adjacent the normal end of the sole, in abutting relation to said shoulder and with said extension interlocked between the shoulder and the heel. 100

4. The method of making shoes which comprises operating upon the heel end of a sole to provide an abutment coextensive with the breast line and a flap extending therebeyond, and to attach the sole to an upper with the abutment against the bottom of the upper, and applying a heel to the upper with said flap in interlocking engagement between the heel and the upper, and with said abutment in abutting relation to the heel breast. 110

5. The method of fitting heel seats of shoes which comprises operating upon the sole across the back to form an abutment coextensive with the breast line in one plane and a flap in another plane, and to attach the sole to the shoe with the abutment side adjacent the shoe bottom and applying a heel to the shoe with the flap therebeneath and in the plane of said abutment, and with said abutment in abutting relation to the heel breast. 120

6. The steps in the making of shoes with heels having concave bases which comprises 130

making a shoe sole with a portion of the sole extending no further under the attaching surface of a heel than may be required to form an inter-engagement between the sole 5 and the heel, attaching the sole to the shoe bottom, shaping such extending portion of the sole to provide a filler for the concavity of the heel, of lesser thickness than the sole proper and to provide a shoulder across the 10 sole, bending the filler across said shoulder, and applying the heel to the shoe bottom, in abutting relation to the filler at the point where it engages the shoulder, with the extension between the upper surface of the con- 15 cavity of the heel and the shoe bottom.

7. The steps in the making of shoes with heels having concave bases which comprises making a shoe sole with one portion of the sole extending to the heel breast portion only, 20 and another portion of the sole extending no further under the attaching surface of a heel than may be required to form an inter-engagement between the sole and the heel, attaching the sole to the shoe bottom shaping 25 such extending portion of the sole to provide a filler for the concavity of the heel, of lesser thickness than the sole proper and to provide a shoulder across the sole, bending the filler across said shoulder, and applying 30 the heel to the shoe bottom in abutting relation to the filler with the heel breast flush with said first portion and with the extension between the upper surface of the con- 35 cavity of the heel and the shoe bottom.

8. A shoe comprising an upper, an out-sole and a heel, said sole being formed with an abutment thereacross and substantially at the breast line and a flap extending over and beyond said abutment, said heel being at- 40 tached to the upper with said flap interlocked therebetween, and located with the heel breast thereof in abutting relation to said abutment.

9. A shoe comprising an upper, an out-sole and a heel, said sole being formed with an abutment thereacross and substantially at the breast line, and a flap extending over and beyond said abutment, said heel being pro- 45 vided with a concave face and attached to the upper with said flap interlocked therebe- 50 tween, and located with the heel breast there- of substantially flush with said abutment, said flap being shaped to substantially fill the concavity of the heel.

55 In testimony whereof I affix my signature.

BENJAMIN W. FREEMAN.
